UNDERWATER CONNECTOR

Filed April 15, 1937

UNITED STATES PATENT OFFICE

2,189,439

UNDERWATER CONNECTOR

Robert Temple, Jr., Pittsburgh, Pa.

Application April 15, 1937, Serial No. 137,073

7 Claims. (Cl. 114—16.4)

This invention relates to apparatus for supplying a fluid pressure connection to an object under water, as, for example, a sunken submarine.

It is the general object of my invention to provide an improved underwater connector whereby fluid can be supplied to or removed from a submerged plate, and particularly to a sunken or injured ship.

Another object of my invention is the provision of improved apparatus for connecting conduits, such as air lines, to an object under water, which apparatus is relatively inexpensive and easily and quickly installed, and which is satisfactory in use.

15 In the accompanying drawing Fig. 1 is a side elevation of one embodiment of connector apparatus constructed in accordance with the principles of my invention with certain of the associated projectile driving mechanism being broken away, and Fig. 2 is a vertical cross-sectional view taken on line II—II of Fig. 1 and illustrating in greater detail certain of the projectile driving mechanism.

Although the improved apparatus of my invention is broadly adapted to provide underwater connections of all sorts, as, for example, ship repair beneath the water line of the hull, connections to submerged tanks, plates, pipes and vessels of all sorts, nevertheless my invention is 30 particularly adapted to the salvage of sunken vessels and to supply air or oxygen to sunken submarines. Hence in the following description and in the drawing the invention has been illustrated and will be described as employed to provide a connection with a metal plate, as, for example, forming the side wall of a sunken vessel.

Having particular reference to the drawing, the numeral 10 indicates a metal plate, as, for example, forming an outer wall of a submerged vessel. Secured in fluid-tight relation to the plate 10 is a cup 12 having an integral endless flange 14 formed on the cup adjacent the lip thereof. A gasket 16, of any suitable type, and received in a recess 17 on the cup, is ordinarily employed between the cup 12 and the plate 10.

Securing the cup 12 to the plate 10 is a plurality of threaded pins 18 which are driven through suitable apertures 20 in the flange 14 and into the metal plate 10, as, for example, by mechanism such as illustrated in my father's Patents Nos. 1,365,869 and 1,365,870. These mechanisms are adapted to drive a pointed projectile, such as the pin 18, under high force and velocity by the explosion of a confined explosive charge. The 55 penetrating power of the pins is, of course, deter-

mined by the amount of explosive material employed. When driving the pins 18, an explosive charge is used which drives the pins only part way through the side of the plate 10, and the threads on the pin or a positive shoulder may 5 be used to stop the pin exactly where desired. Nuts 22 threaded on the pins 18 tighten the cup 12 into fluid-tight relation with the plate 10. A set screw 24 received in an extending portion 26 of the flange may be provided to act when tightened 10 as a lock for the various nuts 22.

Secured to the cup 12 and particularly to a circular hub 30 thereof is a conduit 32 which is adapted to supply fluid under pressure to the interior of the cup 12. The cup 12 likewise is 15 provided with one or more projectile driving mechanisms, each indicated as a whole by the numeral 33, and are constructed generally in accordance with the disclosure of my father's Patents Nos. 1,365,869 and 1,365,870. Particularly, each mechanism includes a barrel 34, a removable breech block 35, a piercing projectile 36, a piston 37 which receives an explosive charge, and a detonating cap 38 integral with the piston. The cap is detonated by a firing pin 39 urged 25 toward firing position by a spring 40 but normally held against movement by a removable safety pin 41. The barrels 34 of the mechanisms 33 are threaded at their ends, as at 42, and are received in suitable tapped recesses 43 provided 30 in the cup in alignment with openings 44 which extend substantially parallel to the axis of the cup 12 and open to the interior thereof. I usually provide a sealing disc 46 of metal, such as copper, between the threaded end 42 of each 35 driving mechanism and the bottom of the tapped recesses 43.

In the practice of the method of my invention the cup 12 when still above water has the conduit 32 and the driving mechanisms 33 secured 40 thereto. The cup and associated mechanisms and conduit are then lowered down into the water and are guided, for example, by a diver, into engagement with the plate 10. When in the desired position relative to the plate, the pointed 45 pins 18 are driven through the apertures 20 of the flange 14 and into the plate 10 by the mechanism or mechanisms of the referred-to patents as handled by the diver. Nuts 22 are then run onto the pins 18 to secure the cup 12 in fluid-tight relation against the side of the plate 10. The set screw 24 may then be tightened to further lock the assembly in place. The projectile driving mechanisms 33 carrying a sufficiently heavy explosive charge to drive their projectiles 36 completely 55

through the plate 10 are now operated by pulling out the pins 41 so that air or other fluid under pressure supplied to the conduit 32 passes through the plate 10 and into the sunken vessel. The slight amount of water trapped within the cup 12 when it is secured in place causes no harm.

In the usual operation the driving mechanisms 33 are left on the cup 12 during the passage of fluid under pressure to the cup 12 and to the other side of the plate 10. In certain instances I have found it advisable to remove the driving mechanisms 33 and use them elsewhere. This can be done inasmuch as the pistons 37 of the driving mechanisms 33 are sufficiently expanded in the barrel of the driving mechanisms as to permit the removal of all but the threaded end 42 of the barrel which can be made as a removable and replaceable part of the barrel.

From the foregoing description it will be recognized that the objects of my invention have been achieved by the provision of apparatus for quickly and positively connecting a conduit carrying fluid to or from a submerged object. The apparatus is relatively inexpensive and can readily be operated and installed by the ordinary diver.

While in accordance with the patent statutes one embodiment of my invention has been illustrated and described in detail, it should be appreciated that the invention is not limited thereto or thereby but is defined in the appended claims.

I claim:

1. Apparatus for supplying fluid under pressure to or withdrawing it from a sunken vessel or the like comprising a cup, an endless flange on the cup adjacent the lip of the cup, a gasket associated with the flange, a conduit secured to the cup and extending to the surface, means explosively driven through the sides of the vessel securing the flange to the vessel in fluid-tight relation therewith, and means associated with the cup and adapted to drive a punch under the impulse of a detonated confined explosive charge through the side of the vessel inside the cup to leave an unobstructed passage through the side of the vessel.

2. Apparatus for connecting a conduit to a plate or the like submerged in water comprising a cup, an endless flange on the cup adjacent the lip of the cup, a gasket associated with the flange, a conduit secured to the cup and extending to the surface, means for securing the flange to the plate in fluid-tight relation therewith, and means associated with the cup and adapted to pierce the plate inside the cup.

3. Apparatus for supplying fluid under pressure to or withdrawing it from a submerged unpre-

pared metal plate or the like comprising a cup, a gasket associated with the cup, a conduit secured to the cup, piercing pins securing the cup to the plate with the gasket between the cup and plate and in fluid-tight relation therewith, and means associated with the cup and comprising a projectile-driving device for piercing an unobstructed hole through the plate inside the cup.

4. Apparatus for connecting a conduit to a metal plate or the like comprising a member, a conduit secured to the member and extending to the inside thereof, explosively driven piercing pins securing the member to the plate in fluid-tight relation therewith, and means associated with the member for chambering an explosive device for puncturing the plate inside the member.

5. Apparatus for supplying fluid under pressure to or withdrawing it from a sunken vessel or the like comprising a flanged cup-shaped member, a conduit secured to the member and extending to the surface of the water, said conduit being adapted to supply fluid under pressure to the member, means explosively driven through the member and the side of the vessel securing the member to the vessel in fluid-tight relation therewith, and means associated with the member to drive a punch-type projectile under the impulse of a detonated confined explosive charge through the side of the vessel inside the member so as to connect the conduit to the inside of the vessel by an unobstructed passage.

6. Apparatus for supplying fluid under pressure to or withdrawing it from a sunken vessel or the like comprising a member, a conduit secured to the member, explosively driven means securing the member to the vessel in fluid-tight relation therewith, and means associated with the member to pierce the side of the vessel inside the member so as to connect the conduit to the inside of the vessel.

7. Apparatus for connecting fluid under pressure to or withdrawing it from a metal plate or the like submerged in water comprising a lipped hollow cup-shaped member, a conduit secured to the member and extending to a source of fluid under pressure, said conduit being adapted to supply fluid without confinement to the interior of the cup-shaped member, means explosively driven through the lip of the member and the plate securing the member to the plate in fluid-tight relation therewith, and means associated with the member to drive projectiles under the impulse of a detonated confined explosive charge through the plate to connect the conduit to the other side of the plate.

ROBERT TEMPLE, JR.

CERTIFICATE OF CORRECTION.

Patent No. 2,189,439.

February 6, 1940.

ROBERT TEMPLE, JR.

It is hereby certified that error appears in the printed specification of the above numbered patent requiring correction as follows: Page 2, second column, line 38, claim 6, after "and" insert explosively driven; and that the said Letters Patent should be read with this correction therein that the same may conform to the record of the case in the Patent Office.

Signed and sealed this 19th day of March, A. D. 1940.

Henry Van Arsdale,
Acting Commissioner of Patents.
